UNITED STATES PATENT OFFICE

HARRY R. ORWICK AND EDWIN J. BOGNAR, OF MASSILLON, OHIO, ASSIGNEES TO
CORUNDITE REFRactories, INC., OF MASSILLON, OHIO, A CORPORATION OF OHIO

GROOVED REFRactory LINING

Application filed October 24, 1929. Serial No. 402,098.

This invention relates to linings for electric furnaces and is particularly directed to a grooved refractory lining for such furnaces.

Refractory linings for electric furnaces of various types are, of course, old and well known per se. Such linings in the past have, however, generally been made in one of the following ways: first, either by tamping in a plastic mass within the furnace which hardens by heating to form an irremovable lining; or, second, by placing refractory bricks or shapes in the furnace and then cementing them together with suitable refractory cements. The first type of lining is very unsatisfactory because when it becomes worn, burnt out, or broken it is difficult to patch or repair and as to the second, this type of lining is objectionable for the same reasons and also because of the liability of such linings to chip and crack or burn out under sustained high heat in the furnace. These linings, furthermore, do not readily lend themselves to cooperation with other linings of the same or different types as there is no way of securing such other linings thereto.

One of the objects of the present invention is to obviate the difficulties and disadvantages inherent in or arising from the use of linings of the above mentioned types and to provide a lining having advantages peculiar to its own construction.

Another object of the invention is to provide a simple, inexpensive, and easily manufactured lining for all types of electric furnaces which is readily accessible in all its parts and which readily cooperates with other linings or similar or other materials.

A further object of the invention is to provide a grooved lining for electric furnaces.

A still further object of the invention is to provide a lining for electric furnaces having corrugations or grooves of a particular kind and direction.

A preferred embodiment of the invention

has been illustrated in the accompanying drawings wherein similar numerals refer to similar parts throughout the several views and wherein:

Figure 1 is a vertical elevation of a furnace lining according to the present invention;

Fig. 2 is a vertical cross section of the lining of Fig. 1; and

Fig. 3 is a view of the underside of a cover provided for the lining.

In the drawings, in detail, a lining 10 has been illustrated which consists of two parts, the first part being a cylindrical portion 11 forming the body of the lining and the second being a cover 12 for the same. This lining in the form illustrated is especially designed for a Detroit electric furnace but can be adapted with minor or suitable variations and changes to other types of electric furnaces or, in fact, to any type of electric furnace which may be evolved in the future.

The cylindrical body portion 11, as shown, comprises a cylinder having one open end 12' and one closed apertured end 13. The open end, which may be termed the upper one, is provided with a channel or groove 14 extending in and around the upper surface of the cylinder wall. The purpose of this groove will be more apparent hereinafter.

The other end of the cylinder is termed a closed apertured end because of the fact that it would be a solid end wall except for the presence of the central aperture 15 provided therein. In the side wall of the cylinder is another aperture 16 of rectangular shape, having a tapered extension 17 at one of its sides, as shown particularly in Figs. 1 and 2. Such an aperture as this may well be provided of required shape to give access to the interior of the lining particularly through the door in the furnace (not shown) which may coincide therewith.

The interior surface of the wall of the cylindrical portion is grooved as at 18 thereby

increasing the area of the wall and furthermore permitting its cooperation with other linings or plastic materials which can be forced while plastic into the grooves. If the 6 grooves 18 are made of a dove-tail nature, that is, with inclined walls so that the wider portion of the groove lays toward the outer surface of the wall of the cylinder, it will be seen that the moldable or plastic material 10 which is placed in the grooves will be effectively gripped so as to be nondisplaceable. While it is not necessary that my corrugations or grooves take a particular direction and form, yet I have found that the grooves 15 as they are shown provide a particularly effective and excellent lining. The grooves 18 in the cylindrical portion are vertical and parallel and may be spaced apart any desired distance, the extent of the grooves themselves 20 being naturally variable. In the closed apertured end 13, the grooves 19 are radial, that is, they join with the lower extremities of the vertical parallel grooves 18 and extend from those points toward the center of said circular closed apertured end 13.

In the cover or lid 12 shown in Fig. 3, the form of the same is seen to be circular and rising from the interior surface thereof, near the outer edge, is an annular ridge or projection 20 which fits into an annular groove 14 in the top of the open end of the cylindrical portion, thereby forming what may be termed an annular tongue and groove connection thus securely closing the lining. 25 Leading from within the annular projection 20 in the cover toward the center of the same are the radial grooves 21 similar to those already mentioned in the closed apertured end 13 of the cylindrical portion. There is 30 likewise a central aperture 22 in the cover portion.

The material of which this lining is made is of a suitable refractory, and a preferred composition consists of Al_2O_3 and SiO_2 . The 45 preferred proportion of these ingredients is approximately 70% Al_2O_3 and approximately 30% SiO_2 , although it will be apparent that these percentages can be considerably varied, if required.

50 With such a lining as we have set forth above, we can readily apply to the grooves a plastic or moldable mixture which can be tamped or pounded into the same and hence anchored or attached to the lining in the firmest manner. It will now be clear why the 55 grooves are preferably made dove-tailed, but it is equally clear that such a formation is not absolutely required, but aids, however, in holding the moldable mixture firmly in position. When the nature of the operations 60 which are carried out in electric furnaces is considered, the fact will be appreciated then that it is imperative that the moldable mixture stick well, for only then will the greatest 65 resistance be offered to abrasion, corrosion

and fluxing actions which tend to destroy the lining.

With the lining of my invention, the metal to be melted in the electric furnace may be of many kinds and the refractory lining with the tamped in moldable mixture is suitable for anything that can be smelted, whereas in the prior known constructions, great limitations are placed upon the furnaces since they were not constructed to stand up to or to withstand the various actions occurring in an electric furnace, wherein diverse materials are used. In fact, with a lining like the present, a single furnace can be used without change in place of a number of furnaces which always had to be hitherto provided for the different kinds of smelting.

The above disclosure is intended to be illustrative rather than limitative, as we may make many changes and modifications in the lining, without, however, departing from the scope and spirit of the invention. The material of which the lining is made and the direction and extent of the various grooves and projections can be altered to suit circumstances and we contemplate making the grooves not only uniform as shown, but also uniform in other directions as well as non-uniform in any direction or directions. The grooves, in other words, may be predetermined or they may be haphazard just so the surface of the lining is increased to receive and grip a moldable mixture which may harden therein, thus either adding to the lining, completing it, or acting in the nature of a patch or repair. The lining, of course, is suitably placed in an electric furnace for which it has been designed so that the side opening in the wall of the cylinder gives access to the interior of the furnace via the furnace door, the apertures in the top and bottom giving access conveniently to the furnace either for adding or withdrawing materials or contents thereto or therefrom.

What we claim as new and desire to secure by Letters Patent is:

1. A refractory lining consisting of a cylindrical body portion having an open end and a closed apertured end, said open end having an annular groove, and a cover member adapted to close said open end and having an annular flange fitting into said groove and interior radial grooves, said body portion having interior parallel grooves and said closed end having interior radial grooves, all said grooves being adapted to receive and interlock therewith a moldable mixture.

2. A refractory lining consisting of a cylindrical body portion and a cover therefor, said body portion having an open end provided with an annular groove, a closed centrally apertured end, and an aperture in its wall, said body portion having also interior

parallel dove-tailed grooves, said closed apertured end having interior dove-tailed radial grooves connecting with the parallel grooves aforesaid at the circumference of the closed end, and said cover having an annular flange adapted to enter the annular groove in the open end of the body portion and being provided with radial dove-tailed grooves and a central opening, said grooves being adapted to receive and retain a moldable mixture.

In testimony whereof, we have hereunto set our names this 22nd day of October, 1929.

HARRY R. ORWICK.
EDWIN J. BOGNAR.
